United States Patent

Des. 235,920
Patented July 15, 1975

235,920

DELEAVER MODULE OR SIMILAR ARTICLE

Andrew L. Alger, Wilmette, and Kim Yamasaki, Lombard,
Ill., assignors to Uarco Incorporated, Barrington, Ill.

Filed Dec. 20, 1973, Ser. No. 426,448

Term of patent 14 years

Int. Cl. D18—99

U.S. CL. D64—11 R

FIG. 1 is a perspective view of two adjacent sides of a deleaver module or similar article showing our new design;

FIG. 2 is a front elevational view;

FIG. 3 is a side elevational view from the left of FIG. 2;

FIG. 4 is a side elevational view from the right of FIG. 2; and

FIG. 5 is a top plan view.

The bottom and rear sides are plain and unornamented.
We claim:

The ornamental design for a deleaver module or similar article, substantially as shown and described.
